UNITED STATES PATENT OFFICE.

HARRY S. WELSH, OF NEW YORK, N. Y.

DISAPPEARING FUNNEL.

1,256,961.

Specification of Letters Patent. Patented Feb. 19, 1918.

Application filed August 30, 1916. Serial No. 117,630.

To all whom it may concern:

Be it known that I, HARRY S. WELSH, a citizen of the United States, and a resident of New York, in the county of New York and State of New York, have invented certain new and useful Improvements in Disappearing Funnels, of which the following is a specification.

This invention relates to improvements in funnels and particularly of types adapted to collapse so as to be folded into a relatively small compass.

One of the principal objects of this invention is to provide a funnel which may be used in connection with the filling nozzle, of a water cooler as applied to automobiles in which the funnel may be inverted and retained inconspicuously within the cooling system of the motor used to actuate the vehicle.

Another object is to provide a funnel which is capable of being expanded so that the contents of a bucket or other filling receptacle used may be readily poured into the water tank surrounding the radiator, and

Finally to provide such funnels of durable and cheap construction, readily applicable without change in the device to which they may be used with.

These and other like objects are attained by the novel design, construction and combination of parts hereafter described and shown in the accompanying drawings, forming a material part of this disclosure, and in which:—

Figure 1 is a vertical sectional view showing the application of the invention, the funnel being in an inverted and collapsed position.

Fig. 2 is a similar view of the same, the funnel being expanded and shown in an operative position.

Fig. 3 is a top plan view of the same, parts being removed to show the construction.

Fig. 4 is a top plan view showing the parts when the funnel is in a position shown in Fig. 1, and,

Fig. 5 is a fragmental view showing a detail of the construction.

In the several views the extreme front portion of a water cooled radiator is disclosed, the radiator being indicated by the numeral 10, the surrounding jacket or 55 cooler 11, and the casing 12; at the top of the jacket 11 is a raised screw-threaded annular hub 14 to which is fitted a sleeve 15 covered by the cap 16, the same being indented or corrugated so as to be manually 60 operated as clearly shown in Fig. 4.

Clamped between the upper edge of the hub 14 and a flange 17, formed with the sleeve 16, is a ring 20 to which are attached a plurality of hooks 21, the same engaging 65 with eyes 22 formed with flexible connecting elements 23 disposed between pairs of metallic segments 25 arranged to form when expanded a conical construction as shown in Fig. 2, the elements 23 being composed 70 of leather or other suitable flexible material and held in place between the segments 25 by means of rivets 26 or other like fastenings.

In operation, when the funnel is not in 75 use, the ring is held between the sleeve 15 and hub 14 with the funnel elements hanging pendant in the space above the radiator. When it is desired to make use of the funnel the sleeve 15 is removed, the funnel and ring 80 withdrawn and re-inserted in a reverse position whereupon the segments spread outward by gravity forming a cone shaped structure, as shown in Figs. 2 and 3, by means of which water in relatively large 85 quantities may be readily entered into the chamber contained in the casing 11.

In order to prevent foreign substance from entering the chamber it is preferred to place over the ring 20 a fine meshed grating 28 thereby avoiding entrance of matter that might be detrimental.

Having thus described my invention, what I claim as new and desire to secure by Letters Patent, is:—

The combination with a radiator for automobiles or the like including a flange and a cap having threaded engagement therewith, of a supporting ring clamped between the flange and cap, said ring having eyes provided along the inner side thereof, flexible strips secured to said rings by means of said

eyes, segmental sections arranged in corresponding pairs with their adjacent edges overlapping the edges of the flexible strips, fastening elements passing through the 5 overlapped edges of the segmental sections and through the edges of the flexible strips whereby the sections will be secured together

in such position as to form a funnel, said sections and strips being foldable downwardly into the radiator.

Signed at New York, in the county of New York, and State of New York, this 2nd day of August, 1916.

HARRY S. WELSH.
